UNITED STATES PATENT OFFICE.

OTTO C. SCHWARZ, OF CHICAGO, ILLINOIS.

CARD FRAME OR MOUNT.

1,076,161.

Specification of Letters Patent. Patented Oct. 21, 1913.

Application filed April 28, 1911. Serial No. 623,938.

To all whom it may concern:

Be it known that I, Otto C. SCHWARZ, a citizen of the United States, and a resident of Chicago, in the county of Cook and State 5 of Illinois, have invented certain new and useful Improvements in Card Frames or Mounts; and I do hereby declare that the following is a full, clear, and exact description thereof, reference being had to the accompanying drawings, and to the characters of reference marked thereon, which form a part of this specification.

This invention relates to improvements in card frames or mounts more especially 15 adapted for mounting souvenir postal cards.

Among the objects of the invention is to provide an inexpensive, light and attractive frame for this purpose, and so arranged that the cards to be exhibited may be readily 20 applied to the frame and withdrawn without liability to distorting or breaking the card.

In the drawing Figure 1 is the face view 25 of a card frame or mount embodying my invention. Figs. 2 and 3 are sectional views taken on the line 2—2 and 3—3, respectively, of Fig. 1. Fig. 4 is a face view of a modified form of the frame or mount. Figs. 5 and 6 are sectional views on lines 5—5 and 30 6—6, respectively, of Fig. 4.

The frame shown in Figs. 1, 2 and 3 comprises a flat plate or member 10 provided with a central opening 11, upper and lower strips 12—12 applied to the front face of 35 said plate or member and side strips 14—14 which extend between and preferably abut at their ends against the inner or adjacent edges of the upper and lower strips. The said strips may be nailed, glued, or otherwise fastened to the plate or member 10. The strips when thus arranged produce on 40 the face of the plate or member 10, in effect, a recess or depression 15 to receive a card to be mounted on the device, and of a length 45 less than the card to be so mounted. The inner marginal parts of the upper and lower strips are undercut at the sides thereof adjacent to the flat plate or member 10, to furnish grooves 16 to receive the ends of 50 a card to be mounted on the device, and also to provide overhanging lips 17 which engage the card to hold the same in place. The said undercut grooves and lips extend preferably to the inner sides of the side strips 14, at the 55 ends thereof. The said side strips 14 are spaced at a distance apart approximately

equal to the width of the card to be mounted on said device, and said side strips and the ends of the undercut grooves serve to hold the card laterally in place.

A card is mounted in the frames by inserting one of its ends into one of the undercut grooves 16, bowing the card slightly at its center and applying its other end to the opposite undercut groove 16. Thereupon the card is allowed to straighten to force both ends of the card beneath the overhanging lips 17. The card is thus held flat against the flat frame member. It is held from moving endwise by the end strips 12 and is held from moving sidewise by the side strips 14. Thus the frame may be hung either in a horizontal or endwise position and the card will be retained securely in place in all positions of the frame.

The central hole 11 is provided to facilitate the removal of a card from the frame and also to facilitate its mounting on the frame. Thus when the card is to be removed, one of the fingers of the person 5 mounting the card is applied through the hole 11, to spring or bow the center portion of the card outwardly, so as to withdraw its ends away from the undercut groove 16 and also to raise the bowed portion of the card above the side strips 14. Thereupon the card may be readily removed. If the finger be placed through the hole 11 when a card is being mounted on the frame, it will add to the ease with which the card may be applied to the frame.

In the construction shown in Figs. 4, 5 and 6, the flat plate or member 20 has an oval or other suitably shaped opening 21 through which the card is designed to be exhibited, said card being applied to the back of the flat frame member. The card is held on the rear face of said member by strips 22—22, one above and the other below said opening 21. Said strips are undercut at 1 their inner or adjacent marginal parts to form grooves 23 to receive the card end edges, and to form overhanging lips 24 to hold the ends of the cards in place. There are provided at the ends of the grooves 23 shoulders 25, which engage the side edges of the card and hold the card from slipping laterally out of the frame or mount. Thus the frame may be hung in both a horizontal or an endwise position.

The opening 21 of the frame or mount shown in Figs. 4, 5 and 6, serves the double

purpose as an opening through which to exhibit the card and also as a means to facilitate the application of the card to and its removal from the frame.

5 I claim as my invention,

A card mount or frame comprising a mount member provided with an opening, two holding bar strips applied to one face of said member at two opposite sides of said 10 opening and spaced apart from each other a distance less than the length of the card to be supported thereby, and provided with undercut grooves having fixed or unyielding bottoms to receive the two opposite end 15 edges of the card to hold the same in flat re-

lation against the mount member, said grooves having end shoulder portions engaging the corner ends of the side edges of the card to hold the same against lateral displacement with respect to the mount 20 member, substantially as described.

In testimony, that I claim the foregoing as my invention I affix my signature in the presence of two witnesses, this 15th day of April A. D. 1911.

OTTO C. SCHWARZ.
